US0D1092102S

(12) United States Design Patent (10) Patent No.: US D1,092,102 S
(45) Date of Patent: * Sep. 9, 2025

(54) DESK

(71) Applicant: ODK TECHNOLOGY PTE. LTD.,
Singapore (SG)

(72) Inventor: Hongbing Zheng, Singapore (SG)

(73) Assignee: ODK TECHNOLOGY PTE. LTD.,
Singapore (SG)

() Term: 15 Years

(21) Appl. No.: 29/911,520

(22) Filed: Sep. 5, 2023

(51) LOC (15) Cl. 06-09

(52) U.S. Cl.

USPC D6/651; D6/655.1

(58) Field of Classification Search

USPC D6/329, 641, 651, 652, 655, 655.1,
D6/655.11, 655.12, 655.14, 655.15,
